STOP MOTION FOR TWISTING AND
WINDING MACHINES

Pacific J. Thomas, Scranton, Pa., assignor to U. S.
Textile Machine Company, Scranton, Pa., a
corporation of Pennsylvania

Application February 12, 1940, Serial No. 318,532

6 Claims. (Cl. 242—37)

This invention relates to machines for twisting and winding yarn of the type in which the yarn is drawn upward off of a spool rotated on a twister spindle and is wound on a take-up roll which is rotated by surface contact between a revolving drum and the take-up roll or the yarn wound thereon. Such machines are commonly known in the trade as "up-twisters."

It is the general object of my invention to provide an improved stop motion for such a machine by which the take-up roll and revolving drum will be immediately separated on breakage or failure of the yarn being wound.

A further object is to provide a stop motion having a lightly balanced detector and having power-actuated releasing mechanism controlled by said detector.

I have also provided an improved construction of guide-eye which is displaceable for doffing and returnable to initial position.

My invention further relates to arrangements and combinations of parts which will be herein-after described and more particularly pointed out in the appended claims.

A preferred form of the invention is shown in the drawings, in which—

Fig. 1 is a front elevation of my improved stop motion applied to a winding machine;

Fig. 2 is a sectional side elevation, taken along the line 2—2 in Fig. 1;

Fig. 3 is an enlarged partial front elevation, with certain parts shown in section;

Fig. 4 is a partial plan view, looking in the direction of the arrow 4 in Fig. 3;

Figs. 5 and 6 are detail sectional side elevations, taken along the lines 5—5 and 6—6 in Fig. 3 respectively; and

Fig. 7 is a partial side elevation of a tension bar.

Referring to the drawings, I have shown parts of a winding machine comprising a spool S mounted on a twister spindle 10 and rotated therewith. I have also shown a take-up roll R rotatably supported in the forked upper end of a swinging frame F and engaging a drum D which is continuously rotated at constant speed, as is also the spindle 10.

The yarn Y is drawn upward from the spool S through a guide-wire 12 and over a fixed guide-roll 14 and is then directed through a yarn guide 15 to the surface of the take-up roll R. The yarn guide 15 is pivotally mounted on a traverse rod 16 which is slidable between supporting guide-rolls 17 mounted in fixed bearing members 18. Any usual mechanism (not shown) may be provided for regularly reciprocating the traverse rod 16, with the result that the yarn is laid on the take-up roll R in a desired helical path which is reversed at each end of the roll.

The parts thus far described in themselves

form no part of my present invention which relates more particularly to the provision of means for stopping rotation of the take-up roll R on yarn breakage and to the provision of an improved pivotal support for the guide-wire 12.

The construction of the guide-wire support is clearly disclosed in Fig. 3, which shows the guide-wire 12 extending through a transverse hole in a headed stud 20 mounted in a recess 21 in a stationary lug 22. A spring 24 is interposed between the bottom of the recess 21 and the head of the stud 20, and the lower face of the lug 22 is transversely notched to receive the guide-wire 12 when in the full line operative position indicated in Figs. 1, 2 and 3 or when in the fully inoperative position indicated in dotted lines in Figs. 1 and 3.

The guide-wire 12 is securely clamped in the transverse hole in the stud 20 by a washer 26 and nut 27, the latter being threaded on the lower end of the stud 20. With this construction, the guide-wire 12 will be securely held against twisting in the stud 20 and may be swung from operative to inoperative position as desired, thereby affording convenient clearance for doffing and replacement of the spools S on the spindles 10. When returned to operation, the guide-wire automatically resumes initial position.

My improved stop motion includes a looped detector wire 30 (Fig. 3) secured by a screw 31 to a control member 32 which is pivotally mounted by bearing lugs 33 to rock on a cross-pin 34. The pin 34 is loosely pivoted to swing about a horizontal axis in a fixed lug 35, and the opposite end of the cross-pin swings vertically in a slot 36 in a fixed lug or bracket 37. Upward movement of the pin is limited by a stud or screw 38 which extends across the slot 36, and downward movement is limited by a tension bar to be described and on which the cross-pin rests. The lugs 35 and 37 are secured to a fixed longitudinally extended bar or frame member 35a (Fig. 4).

The member 32 has an upward extension 40 which is disposed in the path of a block 41 mounted on the under side of the reciprocated traverse rod 16 when the member 32 and projection 40 are in the upright stopping position shown in full lines in Fig. 6.

When the machine is running, however, the yarn Y is threaded through the looped detector wire 30 as indicated in dotted lines in Fig. 6 and the projection 40 is swung rearward by yarn tension out of the path of the block 41. If the yarn Y breaks or runs out, the detector parts move to the full line position shown in Fig. 6 and the block 41 engages the projection 40 and depresses the member 32 with results to be described.

A tension bar 50 (Fig. 2) is slidable both endwise and vertically in a slot 51 (Fig. 3) in the

lug or bracket 37. The bar 50 is provided with an elongated slot 53 (Fig. 2) through which extends a stud 54 (Fig. 4) which is mounted in the swinging frame F. A coil spring 55 is connected at one end to an offset flange 56 forming the rear end of the bar 50 and is connected at its forward end to the stud 54, the spring being under tension between these points of attachment. At its forward end, the bar 50 is provided with a tooth 60 and a recess 61 (Fig. 7), and also with a knob 10 or handle 62.

I will now more fully describe the operation of my improved stop motion. When starting a yarn package, the end of the yarn is wrapped around a fresh or empty take-up roll R, which roll is mounted in the bearings provided at the upper end of the swinging frame F. The bar 50 is then moved rearward and upward by manual pressure on the knob 62 until the tooth 60 passes rearward of a cross stud 64 fixed in the bracket 37 (Fig. 5) and is raised to engage said stud, at the same time putting the spring 55 under increased tension and yieldingly pressing the roll R against the revolving drum D.

The tension of the spring 55 is sufficient to overcome the pressure of a weaker spring 70 (Fig. 2) interposed between a fixed lug 71 and a lug 72 projecting rearward from the frame F. Winding of the yarn then proceeds, with the yarn under sufficient tension to hold the detector member 32 in the inclined inoperative position shown in dotted lines in Fig. 6.

The block 41 is regularly reciprocated with the traverse bar 16 but clears the projection 40 so long as the yarn pulls the member 32 forward out of vertical or operative position. When the yarn breaks or runs out, however, the detector member swings to the full line position in Fig. 6 and the block 41 engages the projection 40, swinging the cross-pin 34 downward and carrying with it the tension bar 50, so that the tooth 60 no longer engages the fixed stud 64 in the bracket 37.

The bar 50 then moves forward to the dotted line position shown in Fig. 5, and the stud 54 (Figs. 2 and 4) engages the rear end of the slot 53, so that the spring 55 no longer exerts a rearward pull on the frame F. The frame F and roll R are then free to be moved forward by the spring 70 (Fig. 2), thus breaking the driving contact between the roll R and the drum D. Rotation of the roll R thereupon promptly ceases.

From the foregoing description it will be clear that the yarn Y is not required to actuate any releasing mechanism but merely to hold the projection 40 out of the path of the block 41 until yarn breakage occurs. Thereafter, the parts are released by the power-actuated block 41, thus providing ample and positive releasing force which becomes active as soon as the yarn Y releases the detecting member.

It will be understood that a separate detecting device is provided for each spindle 10 and roll R, and that the operation of these devices is independent, so that the stopping of one roll does not effect the winding operations of the remaining rolls.

Having thus described my invention and the advantages thereof, I do not wish to be limited to the details herein disclosed, otherwise than as set forth in the claims, but what I claim is:

1. In a winding machine of the "up-twister"

type, in combination, a take-up roll, a swinging frame on which said roll is pivotally supported, a tension bar having a slideable connection with said frame, a tension spring connecting said frame and said bar, a latch-pin with which said bar may be manually engaged, a detecting member, a cross rod on which said member is pivoted, and a positively moved actuator for said member, said member having a portion which is positioned for engagement by said actuator when said member is out of yarn engagement and which is clear of said actuator when said member is engaged by the yarn, and said cross rod overlying the latched portion of said bar and being effective to depress and release said bar when said member is engaged and moved by said actuator.

2. The combination in a winding machine as set forth in claim 1, in which means is provided to swing said frame and take-up roll forward when said tension bar is released.

3. The combination in a winding machine as set forth in claim 1, in which the detecting member comprises an elongated wire loop through which the yarn is drawn during a winding operation.

4. In a winding machine of the "up-twister" type having a take-up roll and a driving drum, in combination, a frame for said take-up roll mounted to swing about a fixed pivot, a stop motion comprising a device to apply pressure to the take-up roll during winding, manual means to latch said pressure-applying device in operative position, a movable detecting member held in a displaced position by yarn engagement, a positively moved actuator effective to engage and move said member when said member is not displaced, and connections through which such engagement and movement of said member is effective to release said pressure-applying device.

5. In a winding machine of the "up-twister" type having a take-up roll and a driving drum, in combination, a frame for said take-up roll mounted to swing about a fixed pivot, a stop motion comprising a device to apply pressure to the take-up roll during winding, manual means to latch said pressure-applying device in operative position, power-actuated means to release said device, and a freely pivoted detecting member which renders said power-actuated means operative to release said pressure-applying device when said member is not engaged by the yarn.

6. In a winding machine of the "up-twister" type having a take-up roll and a driving drum, in combination, a stop motion comprising a device to apply pressure to the take-up roll during winding, manual means to latch said device in operative position, a regularly reciprocated releasing element, a cross-pin, a detecting member pivotally mounted on said cross-pin and held by yarn engagement out of position to be normally engaged by said reciprocated element, and a fixed element having a vertical slot, said cross-pin being mounted at one end on a fixed pivoted and having its opposite end positioned to swing in said vertical slot and said opposite end of said cross-pin being moved downward in said slot to release said pressure-applying device when said detecting member is released by yarn failure and is engaged by said reciprocated element.
